(57) **CLAIM**

The ornamental design for a bluetooth rechargeable mini speaker, as shown and described.

DESCRIPTION

FIG. 1 is a top, front, perspective view of a bluetooth rechargeable mini speaker showing my new design in an open condition;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a cross-sectional view thereof along line 8-8 in FIG. 2;

FIG. 9 is a cross-sectional view thereof along line 9-9 in FIG. 2;

FIG. 10 is an enlarged detail at 10 in FIG. 8;

FIG. 11 is a top, perspective view thereof showing my new design in a closed condition;

FIG. 12 is a front view thereof;

FIG. 13 is a rear view thereof;

FIG. 14 is a left side view thereof; and,

FIG. 15 is a right side view thereof.

The broken lines in the drawings illustrate environmental material that forms no part of the claimed design.
